UNITED STATES PATENT OFFICE.

EDWARD B. HESS, OF NEW YORK, N. Y., ASSIGNOR TO ROYAL TYPEWRITER COMPANY, OF HOBOKEN, NEW JERSEY, A CORPORATION OF NEW JERSEY.

WRITING-MACHINE.

No. 861,978.

Specification of Letters Patent.

Patented July 30, 1907.

Application filed April 22, 1907. Serial No. 369,492.

To all whom it may concern:

Be it known that I, EDWARD B. HESS, a citizen of the United States of America, residing in the borough of Brooklyn, city and State of New York, have invented certain Improvements in Writing-Machines, of which the following is a specification.

This invention relates to a novel arrangement of paper feed devices and an alining or scale-bar in a front strike writing machine.

- 10 In the accompanying drawings: Figure 1 is a plan; Fig. 2, a front elevation; Fig. 3, a detached plan showing the paper feed or pressure rolls that coöperate with the platen; Fig. 4, an end elevation looking from the right hand side of the machine; Fig. 5, a section on the line 5, 5, of Fig. 2; Fig. 6, a detail section showing all the parts in normal position; Fig. 7, a like view showing the scale-bar raised with the front and rear pressure rollers still in engagement with the platen; Fig. 8, a like view showing the pressure rolls thrown 15 out of engagement with the platen; Fig. 9, a detail elevation showing the gear connection by which the rear feed roll shaft is positively driven from the platen; Fig. 10, a section on the line 10, 10, of Fig. 3, omitting the paper table and pan; Fig. 11, a plain view similar 20 to Fig. 3 showing a modification; and Fig. 12, a section similar to Fig. 5 but on line 12 of Fig. 11.

a, a are the carriage side plates in which is mounted to turn shaft *b* of the usual platen *c*. Below the platen is located a frame curved to conform to the contour of the platen and shown as composed of three plates one *d* at each side or end of the frame and one *d'* intermediate the ends of the frame. These plates may have the general configuration shown in Fig. 10 and may be united by a tie rod *d''*. To their rear upwardly 30 extending parts is secured a section *e* of the downwardly extending table. In the upper edges of the plates *d*, *d'* immediately in front of the table section *e* are formed open bearings for the shaft *f* or the rear feed roll *f'* shown as formed in two sections; and near 35 their forward ends the plates are formed with like open bearings for the reception of shaft *g* of the front feed roll *g'* shown in Fig. 3 as having two sections and in Fig. 11 four sections. In the interval between the bearings for the front and rear feed roll shafts there is 40 secured to the plates *d*, *d'*, a paper pan *e'* serving to direct the paper around the platen and upwardly to the pressure or feed roll *g'*. The feed or pressure roll *f'* is of somewhat larger diameter than the front roll *g'* and is preferably located as shown in a plane somewhat above 45 the latter. Both are, however, located suitably below a horizontal plane passing through the axis of the platen and are respectively in front and in rear of a vertical plane passing through the platen axis. The ends of shaft *f* fit between downwardly extending jaws 50 at the ends of flat links *z* extending rearwardly and

pivoted at *i* to the side plates of the carriage. These swinging links act primarily as guides for the pressure roll frame which is drawn upwardly toward the platen to bring the rolls in contact therewith by two coiled springs *l* applied one at each end of the frame and each 60 extending from a forward projection *j* on a cross shaft *j'* to a projecting stud *k* on the outer face of plate *d*. Beneath this frame is a rock shaft *m* to the end of which outside of the right hand side plate *a* of the carriage is applied a lever arm *m'*; and secured to the shaft near 65 each of its ends is a radial arm *n* extending upwardly and rearwardly to such position as when carried downward it will engage the stud *k*.

The hub of the lever arm *m'* has two flat faces against which a flat plate spring *m''* bears to hold the parts in 70 normal position or in position with the pressure rolls drawn away from the platen. By movement of the lever arm *m'* rearwardly, the projections *m* may be caused to strike the lugs *k* and depress the roll and pan frame in which position it will be held by the spring 75 *m''*. The normal position is shown in Fig. 6, and in Fig. 8, the rolls are retracted from the platen.

When the pan and front and rear feed rolls are drawn downwardly by the radial arms *m*, they all descend vertically, or substantially so and the extent of movement of the rear feed roll, pan and front feed roll away from the surface of the platen is uniform, or substantially so. That is to say the frame comprising the front and rear feed rolls and interposed pan descends bodily so that the clearance between the front and rear feed 80 rolls and the surface of the platen is the same, or substantially so. The action is quite different from what would occur if the frame were pivoted in rear of the rear feed roll and rocked about such pivot in its movement away from the platen. The behavior of applicant's devices affords more perfect control of the paper in the machine—particularly when a plurality of sheets are being used. The pressure roll frame may properly be described as a "floating" frame, or as one loosely supported, whose behavior is quite unlike what it would be if 85 it rocked about a fixed axis. It has the capability of adapting or adjusting itself to the platen so as to maintain proper engagement of both the front and rear rolls therewith even though one of them may have become flattened, or worn, or the platen may have lost its 90 exact circular contour. The general arrangement described is rendered more efficient, it is believed, when the rear feed roll is positively driven from the platen at the same surface speed as the latter.

This invention therefore further provides that in an 105 organization of this kind, the rear roll shaft shall be positively driven from the platen at the same surface speed as that of the platen. This may be readily accomplished by a gear *o* at one end of the platen meshing with a smaller gear *p* on the end of the roll shaft *f*. The 110

gears o , p are so proportioned that on rotation of the platen the roll or rolls f' will be rotated at such speed that their surfaces will move at the same speed as that of the platen. The depth of the gear teeth is such as to permit of the depression of the roller and pan frame without carrying the teeth out of engagement. Experience has demonstrated that an organization of this kind has high efficiency in feeding around the platen single sheets or multiple sheets for manifolding.

10 As illustrated, the projecting arms n , move through a substantial distance before engaging the lugs k . The parts are so arranged for the following purpose which constitutes another feature of this invention. Loosely mounted on the rock shaft m adjacent its ends are two 15 forwardly projecting arms q in the outer ends of which are pivoted upwardly and forwardly extending arms q' between the upper ends of which extends an alining or scale-bar r . Coiled springs s connecting the arms q , q' tend, by their reaction to draw the scale bar against the 20 face of the platen. Other springs t connect the arms, which are loose on the rock shaft with the projecting arms n fast on the rock shaft. In the normal position of the parts illustrated in Figs. 1 and 6, the scale bar occupies a position about one letter space below the 25 printing point u . During the first part of the downward movement of the radial arm n spring t couple the arm n with arm q and draws the latter up thus raising the scale bar to the printing line as shown in Fig. 7 without disengaging the pressure rolls from the platen.

30 This upward movement of the scale bar is limited by adjustable eccentric stops v one on each side plate of the carriage and against which the arms q abut. Further rearward movement of the lever arm m' will cause the radial arms n to engage lugs k on the roller 35 and pan frame and carry it downwardly as indicated in Fig. 8. It is preferred that as shown the plates d should be extended upwardly and rearwardly to support the section e of the paper table. That, however, is a matter of choice. The upper part e' of the paper table is 40 detached from the section e and hinged as usual upon a rod extending between the side plates. w , w indicate front paper clamps mounted upon the cross bar j and movable longitudinally thereof. They form no part of this invention.

45 Figs. 11 and 12 show a slight modification. The pan e^2 has its front edge extended to reach beyond the sections (four being shown) of the front feed roll between the sections thereof. In other words the pan is extended and its front edge recessed as at x to receive the 50 sections of the feed roll. The part e of the paper table that is supported by the rearward extensions of the frame plates d , d , d' has a right-angle flange turned

down at it.

- I claim:

55 1. In a visible writing machine, a rotatable platen, front and rear feed rolls below the axis of the platen, a frame in which they are mounted, spring acting means serving normally to maintain the rolls in contact with the platen and means for bodily depressing the roll carrying frame to thereby move both the front and rear rolls substantially corresponding distances away from their normal points of contact with the face of the platen.

60 2. In a visible writing machine, a rotatable platen, front and rear feed rolls below the axis of the platen, a frame in which they are mounted, a paper-pan, constituting part of the frame, arranged below the platen and between the front and rear feed rolls, spring acting means serving nor-

mainly to maintain the rolls in contact with the platen and means for bodily depressing the roll carrying frame to thereby move both the front and rear rolls substantially 70 corresponding distances away from their normal points of contact with the face of the platen.

3. In a visible writing machine, a rotatable platen, front and rear feed rolls below the axis of the platen, a frame in which they are mounted, spring acting means serving 75 normally to maintain the rolls in contact with the platen, means for bodily depressing the roll carrying frame to thereby move both the front and rear rolls substantially corresponding distances away from their normal points of contact with the face of the platen, and means whereby 80 when the platen is rotated the rear feed roll is positively rotated at the same surface speed as that of the platen.

4. In a visible writing machine, a rotatable platen, front and rear feed rolls below the axis of the platen, a frame in which they are mounted, spring acting means serving normally to maintain the rolls in contact with the platen, means for depressing the roll carrying frame to thereby move both the front and rear rolls substantially corresponding distances away from their normal points of contact with the face of the platen, a gear mounted concentrically to the platen and rotating therewith and a gear on the shaft of the rear feed roll with which said gear meshes, the ratio of the two gears being such that the rear feed roll will be driven at the same surface speed as that of the platen and the depth of engagement of the teeth being such that they will not pass out of engagement when the roll frame is depressed. 85 90 95

5. In a visible writing machine, a rotatable platen, front and rear feed rolls below the axis of the platen, a frame below the platen adapted to move bodily toward and from the platen and having bearings for the shafts of the front and rear feed rolls and, intermediate such bearings, a curved pan for guiding the paper, means for normally pressing the frame upwardly for holding the rolls in yielding engagement with the platen and means for depressing the frame bodily to carry the rolls substantially corresponding distances away from their normal points of contact with the platen. 100 105

6. In a visible writing machine, a rotatable platen, front and rear feed rolls below the axis of the platen, a frame below the platen, adapted to move bodily toward and from the platen and having bearings for the shafts of the front and rear feed rolls and, intermediate such bearings, a curved pan for guiding the paper, means for normally pressing the frame upwardly for holding the rolls in yielding engagement with the platen, means for depressing the frame bodily to carry the rolls substantially corresponding distances away from their normal points of engagement with the platen, and pivoted guide links engaging the roller frame. 120

7. In a visible writing machine, a rotatable platen, front and rear feed pressure rolls below the axis of the platen and between such rolls a paper pan and means whereby the rolls and pan may be moved bodily downward to carry the rolls substantially equal distances away from their points of normal engagement of the platen. 120 128

8. In a visible writing machine, a rotatable platen, front and rear feed pressure rolls below the axis of the platen and between such rolls a paper pan, means whereby the rolls and pan may be moved bodily downward to carry the 130 rolls substantially equal distances away from their points of normal engagement of the platen and means for positively driving the rear feed roll at the same surface speed as that of platen.

- as that of platen. 135
9. In a visible writing machine, a rotatable platen, a pressure roll frame comprising plates arranged under the platen and transversely to the axis thereof and a paper pan extending between the several plates, said frame being mounted to move bodily toward and from the platen, front and rear pressure rolls whose shafts are below the axis of the platen and are mounted in bearings in said plates, spring devices for normally urging the frame upwardly to bring the rolls into engagement with the platen and means for depressing the frame to carry the rolls substantially equal distances away from their points of normal engagement with the platen. 145

10. In a visible writing machine, a rotatable platen, a pressure roll frame comprising plates arranged under the

- platen and transversely to the axis thereof and a paper pan extending between the several plates said frame being adapted to move bodily downwardly away from the platen, front and rear pressure rolls below the axis of the platen 5 whose shafts are mounted in bearings in said plates, spring devices for normally urging the frame upwardly to bring the rolls into engagement with the platen, means for depressing the frame to carry the rolls out of engagement with the platen, and guide links pivoted to the carriage 10 frame and having bearings in which lies the shaft of the rear feed roll.
11. In a visible writing machine, a platen, front and rear feed rolls mounted respectively in front and rear of a vertical line passing through the axis of the platen, a paper pan intermediate the front and rear feed rolls and means for simultaneously moving the rolls downwardly to carry them substantially equal distances away from their normal points of engagement with the surface of the platen.
12. In a visible writing machine, a platen front and rear feed rolls mounted respectively in front and rear of a vertical line passing through the axis of the platen, a paper pan intermediate the front and rear feed rolls, means for simultaneously moving the rolls downwardly to carry them substantially equal distances away from their normal points of engagement with the surface of the platen, and means for positively driving the rear feed roll at the same 25 surface speed as that of the platen.
13. In a visible writing machine, a platen, front and rear feed rolls arranged below the horizontal plane passing through the axis of the platen and respectively in front and rear of a vertical plane passing through said axis, means for simultaneously moving both rolls downwardly, in substantially vertical lines, out of engagement with the 30 surface of the platen and means for positively driving the rear feed roll at the same surface speed as that of the platen.
14. In a visible writing machine, a platen, a frame comprising a paper pan located beneath the platen and 35 forming generally to the contour thereof and a paper table section extending upwardly and rearwardly away from the platen, front pressure rolls mounted in said frame in front of the paper pan and a rear pressure roll mounted in said frame between the paper pan and section of paper table, spring acting means acting upon the frame to hold the rolls in engagement with the face of the platen and means for depressing the frame bodily in a substantially vertical direction to carry the rollers out of engagement with the platen.
15. In a visible writing machine, a platen, a frame comprising a paper pan located beneath the platen and 40 forming generally to the contour thereof and a paper table section extending upwardly and rearwardly away from the platen, front pressure rolls mounted in said frame in front of the paper pan and a rear pressure roll mounted in said frame between the paper pan and section of paper table, spring acting means acting upon the frame to hold the rolls in engagement with the face of the platen and means for depressing the frame bodily in a substantially vertical direction to carry the rollers out of engagement with the platen, and means for positively driving the rear roll from the platen at the same surface speed as that of the latter.
16. In a visible writing machine, a platen, front and rear feed rolls normally engaging the face of the platen, a 45 scale bar normally located below the line of print, means acting during the early stage of its movement to raise the scale bar to the line of print and during the final stage of movement to move the front and rear feed rolls out of engagement with the face of the platen.
17. A visible writing machine comprising a platen a paper receiving pressure roll, a paper delivery pressure roll, and a spring supported floating or loosely mounted frame in which the rolls are carried adapted to adjust itself to the platen to maintain uniform contact of both rolls therewith. 75
18. A front strike writing machine comprising a platen, front and rear pressure rolls lying below a horizontal plane passing through the axis of the platen, and a spring supported floating or loosely mounted frame in which the rolls are carried adapted to adjust itself to the platen to maintain uniform contact of both rolls therewith. 80
19. A front strike writing machine comprising a platen, front and rear pressure rolls lying below a horizontal plane passing through the axis of the platen, a paper pan between the two rolls and a spring supported floating or 85 loosely mounted frame carrying the rolls and pan and adapted to adjust itself to the platen to maintain uniform contact of both rolls therewith.
20. A front strike writing machine comprising a platen, front and rear pressure rolls and a spring supported 90 frame carrying the rolls and adapted to move about an axis that is movable up and down relatively to the platen.
21. A front strike writing machine comprising a platen, front and rear pressure rolls and a spring supported frame carrying the rolls and adapted to move about a spring supported axis that is movable up and down. 95
22. A visible writing machine comprising a platen, front and rear pressure rolls, a frame carrying the rolls and links pivoted at their rear ends to the frame of the platen carriage and pivotally connected at their free front ends with the pressure roll frame. 100
23. A visible writing machine comprising a platen, front and rear pressure rolls, a frame carrying the rolls and adapted to move about a spring supported axis that is movable up and down and means for positively driving the rear pressure roll from, and at the same surface speed as, the platen. 105
24. A front strike writing machine, comprising a platen, a paper receiving or rear pressure roll and a frame carrying the roll and adapted to move about a spring supported axis that is movable up and down and located in rear of the platen. 110
25. A visible writing machine, comprising a platen, a paper receiving or rear pressure roll, a frame carrying the roll and adapted to move about a spring supported axis that is movable up and down and means for positively driving the pressure roll from, and at the same surface speed as, the platen. 115
26. A front strike writing machine, comprising a platen and paper feed devices coöperating therewith and movable about a spring supported axis that is movable up and down and located in rear of the platen. 120
27. A visible writing machine, comprising a platen, paper feed devices coöperating therewith and movable about a spring supported axis that is movable up and down and means for moving and locking the feed devices out of operative relation to the platen. 125
28. A visible writing machine, comprising a platen, paper feed devices coöperating therewith, and a floating or loosely mounted spring supported frame carrying the feed devices. 130

In testimony whereof, I have hereunto subscribed my name.
